STARTING MECHANISM FOR AUTOMOBILES.

1,246,206.

Specification of Letters Patent.

Patented Nov. 13, 1917.

Application filed August 6, 1915. Serial No. 44,005.

To all whom it may concern:

Be it known that I, CHARLES E. WILSON, a citizen of the United States, and a resident of Wilkinsburg, in the county of Allegheny and State of Pennsylvania, have invented a new and useful Improvement in Starting Mechanisms for Automobiles, of which the following is a specification.

My invention relates to starting mechanisms for automobiles and particularly to such mechanisms as embody dynamo-electric machines having reciprocating armatures for effecting the operative connection of the dynamo-electric machines to the shafts of internal combustion engines.

My invention has for its object to provide a simple and efficient arrangement whereby the armature of a dynamo-electric machine may be reciprocated longitudinally with a strong force while little or no torque is effective to rotate the armature.

The successful operation of starting mechanisms of the same general character as that of my invention depends upon the provision of means whereby the armature may be shifted longitudinally to effect the meshing of the coacting gear wheels which operatively connect the electric motors to the engines of the motor vehicles while little or no torque is applied to the armature. Otherwise, the armature rotates at such a high rate of speed, upon the closing of the motor circuit, that the meshing of the gear wheels is rendered difficult or the coacting teeth are damaged as a result of the impact when they are brought into engagement. When a relatively high torque is exerted upon the armature, the lateral pressure upon the gear teeth renders it difficult to effect the complete meshing of the gear wheels even when the initial engagement of the teeth has been effected.

In the present arrangement, a dynamo-electric machine is provided with an armature having a winding of an abnormally large number of ampere turns, as, for example, double the ampere turns of the series field-magnet winding. When the armature winding is energized, the armature reaction is increased in a corresponding degree. The magnetic pull exerted upon the field-magnet poles is also increased in substantially the same proportion.

When the armature only is connected in

circuit with a source of current, the armature reaction is strong enough to effect the shifting of the armature into its central position and thereby effect the engagement of the coacting gear wheels. Since the field-magnet windings are not energized, no torque is effective to rotate the armature, and the gear wheels are easily meshed. In order to insure proper conditions for commutation, a compensating field-magnet winding is provided. Otherwise, an abnormal distortion of the magnetic field is caused by reason of the armature reaction during the normal operation of the motor.

The details of my invention will be described in connection with the accompanying drawing, in which Fig. 1 is a view, partially in section and partially in elevation, of a portion of an engine fly wheel, with my invention applied thereto. Fig. 2 is a diagrammatic view of circuits and apparatus embodying my invention.

The fly wheel 1 of an internal-combustion engine, only a portion of which is shown, is provided with gear teeth 2. An electric motor 3, which is supported by any suitable means adjacent the fly wheel, has a field-magnet core structure 4, a series field-magnet winding 5 and a compensating field-magnet winding 6.

The motor armature 7 is provided with a winding the ampere turns of which may greatly exceed the ampere turns of the series field-magnet winding 5.

The armature 7 and the armature shaft 8 are arranged for longitudinal movement relatively to the field-magnet frame. A spring 9, which is interposed between a collar member 10 on the armature shaft and one of the bearings 12, tends to maintain the armature in a displaced position relatively to the core structure. The commutator cylinder 13 is of such length that it is always in engagement with coacting brushes 14 that are secured to the motor frame. A pinion 15, which is mounted on the armature shaft 8, coacts with the gear teeth 2 in the engine fly wheel.

The electrical circuits of the motor 3 and the controlling means therefor are diagrammatically illustrated in Fig. 2. A movable switch member 16 coacts with a contact segment 17 to connect a battery directly in circuit with the armature winding, the field-

magnet windings 5 and 6 being open-circuited when such connection is made. When the switch member 16 engages contact member 18, the working circuit of the motor is completed through the series field-magnet winding 5, the compensating field magnet winding 6 and the motor armature.

It may be assumed that the various parts are in their respective illustrated positions, 10 with the pinion 15 out of engagement with the gear teeth 2 and the switch member 16 in its inoperative or "off" position. To start the engine, the switch member 16 is actuated into engagement with the contact segment 17 15 to complete a circuit through the motor armature. Because of the relatively large number of ampere turns in the armature winding, a strong magnetic pull is exerted upon the field-magnet poles which is sufficient to shift the armature to its central position against the force of the spring 9.

During the longitudinal movement of the armature to effect the engagement of the pinion 15 with the gear teeth 2, the field-magnet windings are de-energized, and there is substantially no torque applied to the armature. The residual magnetism of the field-magnet poles may cause a slight rotation of the armature but such action assists 30 in effecting the initial engagement of the gear teeth.

The switch member 16, which has been actuated with a continuous movement, engages the contact member 18 at substantially the 35 same time that the armature reaches its central position. The normal working circuit of the motor, including the field-magnet windings 5 and 6, is thus completed, and the motor then operates to crank the engine.

40 When the engine starts under its own power, the switch member 16 is actuated to open the motor circuit. It is preferable that the switch mechanism be so arranged that the movable member 16 is actuated continuously in one direction in order that the cycle of connections may not be reversed in stopping the motor. The armature 7 will then be returned to its displaced position by the spring 9, which has been under compression.

45 If the operator fails to open the motor circuit immediately after the engine starts, the motor will be driven at a rapidly increasing speed. The counter electromotive force of the motor is thereby increased to reduce the 50 current traversing its windings to such value that the longitudinal pulls exerted by the field-magnet poles is less than the force of

the spring 9, whereupon the armature is shifted to its displaced position, and the pinion 15 is disengaged from the gear teeth 2. It is clear, therefore, that no damage 60 may be caused by failure to open the switch at the instant the engine starts.

Many modifications will occur to those skilled in the art to which my invention 65 pertains, and it is to be understood that such changes may be made as fall within the scope of the appended claims without departing from the spirit of my invention.

I claim as my invention:

1. In a starting mechanism, the combination with an engine member, and a member 75 for coacting therewith, of a dynamo-electric machine having a longitudinally shiftable armature connected to said coacting member, and means for energizing said armature only to effect the connection of said members.

2. In a starting mechanism, the combination with an engine member, and a member 80 for coacting therewith, of a dynamo-electric machine having a longitudinally shiftable armature connected to said coacting member, and means for controlling said dynamo-electric machine whereby the armature is shifted by its reaction only to effect the operative 85 engagement of said members.

3. In a starting mechanism, the combination with an engine member, and a member 90 for coacting therewith, of a dynamo-electric machine having a longitudinally shiftable armature connected to said coacting member, and means for successively completing the armature circuit only of said dynamo-electric machine and completing a working circuit comprising the armature winding and 95 the field-magnet winding of said dynamo-electric machine.

4. In a starting mechanism, the combination with an engine member, and a member 100 for coacting therewith, of a dynamo-electric machine having a longitudinally shiftable armature connected to said coacting member, and means for successively completing the armature circuit only of said dynamo-electric machine to shift the armature longitudinally and thereby effect the operative 105 connection of said members, and completing a working circuit for said dynamo-electric machine to rotate said armature.

In testimony whereof, I have hereunto 110 subscribed my name this 30th day of July, 1915.

CHARLES E. WILSON.
